ELECTRIC RAILWAY SYSTEM.

(Application filed Apr. 9, 1901.)

(No Model.)

THE NORRIS PETERS CO., PHOTO-LITHO, WASHINGTON, D. C.

UNITED STATES PATENT OFFICE.

JOHN C. HENRY, OF DENVER, COLORADO; SUSIE A. HENRY, EXECUTRIX OF
SAID JOHN C. HENRY, DECEASED, ASSIGNOR TO STANLEY ELECTRIC
MANUFACTURING COMPANY, A CORPORATION OF NEW JERSEY.

ELECTRIC-RAILWAY SYSTEM.

SPECIFICATION forming part of Letters Patent No. 707,844, dated August 26, 1902.

Application filed April 9, 1901. Serial No. 55,102. (No model.)

To all whom it may concern:

Be it known that I, JOHN C. HENRY, a citizen of the United States, residing in Denver, county of Arapahoe, State of Colorado, have 5 invented certain new and useful Improvements in Electric Railways, of which the following is a specification.

My invention relates more particularly to what is known as the third-rail system, being also of the safety class, the apparatus being so arranged that the current is supplied only to the sections of track which are occupied by trains. The approach of the train automatically switches the current from the 15 feeders to the working conductors and breaks the connection after the train has passed over the section. The same operation also operates a block-signal system which prevents the same block or track section from being 20 occupied by more than one train at a time, thus avoiding danger from collisions. The working conductors are arranged on the surface of the roadway and are protected in a novel manner, so as to avoid all danger to 25 animals and pedestrians at any time. The circuits are not grounded, so that they are not affected by accidental grounds, and their arrangement may be similar to the well-known distribution arrangement as used in con- 30 duct roads, such as are provided with switches to change the polarity of the working conductors to relieve them of the objectionable effect of double grounds. In order to connect the working conductors with the source 35 of supply, I prefer to use a small alternating current to operate the switches, the general scheme of which is shown in my Patent No. 509,312 of November 21, 1893. The switch is of the most simple and reliable kind, the 40 circuit being closed only when the track-rails are short-circuited by the wheels and axles of the cars.

In the drawings, Figure 1 shows a section of the arrangement where the double track 45 is used and where the current is distributed on the three-wire system. Fig. 2 is a section of the track and working conductor, showing diagrammatically the switch used to connect the working conductors with the

source of supply. Fig. 3 shows one form of 50 trolley. Fig. 4 shows a modification thereof.

Referring to Fig. 1, A represents a pole located centrally between the track-rails, which pole carries the supply-conductors and also the semaphore-signals. For convenience I 55 have also shown attached thereto a box which contains a rotary converter, a static converter, and a reverse-switch. Below the track are shown magnetically-operated switches whose office is to open or close the connections between the working conductors and source of supply. The main current is supplied, preferably, on the three-wire system to the conductors 1, 2, and 3, which are shown mounted on the top of the pole, branch wires 60 leading therefrom through the pole down to the translating devices. Wires 4 and 5 carry a small alternate current which may be supplied from any source or station. I prefer, however, to arrange for this current by converting from the direct-current feeders. The box D contains the motor-generator E, driven by the direct current and generating an alternating current, which is constantly supplied to the primary of the transformer F. This in 65 turn supplies a local current which terminates at the track-rails J', J², J⁴, and J⁵. Included in the local circuit are the solenoids B and B', which operate the danger-signal C or C', and also the magnet-switch K and K', 80 so that when the track-rails are short-circuited these magnets are excited and the danger-signal C is hoisted and current is switched onto the conductors P and Q.

To more fully describe the operation we will 85 refer to the right-hand track only. The current is taken from wire 3 on top of the pole, down through the hollow pole by wire 3', through switch L to the working conductor P. From there it passes through the motor 90 back to conductor Q through switch L, thence by wire 2 up through to mutual wire 2 on top of the pole. The alternate current is supplied from the rotary converter E to the primaries of the different converters, the latter 95 of which are supplied to each block or section of the road, which would in practice be one-half a mile apart. It is understood that the

rotary converters will be only needed for, say, each five miles of roadway. The current supplied from the secondary source passes from the transformer by wire 6 through the 5 pole to the magnet B, thence by wire 7, down to the pole through the magnet K to the track-rail J², the other end terminating, as shown, in the track-rail J'. When the wheels of the axle I touch the track-rails J' and J², they 10 complete the alternate-current local circuit. This actuates the switch L, connecting the working conductors with the main source of supply and raising the semaphore to the danger position. The local devices (semaphores 15 and switches) are thus actuated by a circuit which is supplied from the main or working circuit by an inductive connection, and this inductive connection is subdivided, first, by the rotary converters, and, second, by the 20 stationary converters. The advantage of this arrangement is that it prevents dangerous local short circuits being developed by accidental contact of a person or object with the track. In order that the local devices on 25 the track-sections may respond to the presence of a train on the section, so as to close the working connection, &c., it is necessary that the track-sections should be normally connected with an energizing circuit. In 30 other words, they must be "live" circuits. If they were connected directly to the main working circuit of, say, five hundred volts potential, the consequences of a person or object making a connection with same would 35 be injurious to the person and to the system, as a local short circuit would result, at which a large part of the total energy of the main line might be concentrated; but by applying the electrifying connection to the track-section 40 through distributed induction devices the amount of energy that is liable to concentrate at any one point on occurrence of a short circuit is limited to the capacity of one of such devices. Owing to the expense of a 45 multitude of rotary converters, I prefer to provide a limited number of same, as stated, and to further subdivide the electrifying connection by a number of subsidiary converters of the stationary type, the alternating nature of 50 the current in the secondary circuit conducting to this end. It will be understood that such alternating current may be capable of effecting the operation of the switch and semaphore magnets, the same being properly constructed to respond to such currents. For 55 the working current that operates the train-motors it is desirable to use a direct current, as an alternating current is not adapted to such a purpose without the use of extra conductors and trolleys.

The third rail comprises a supporting I-beam J, of iron, heavy in section and with its top and bottom flanges bent cold in the form shown. This is done to add to its rigidity 60 and stiffness, and to leave a receptacle or aperture wherein a plastic material may be

molded in and keyed or wedged by the dovetailed or undercut form of the aperture. The rounding surface makes it easier for wagons and such to pass over without shock. It will 70 be necessary to bend these flanges after the beam has been rolled, as it will be inconvenient to make the form shown by the ordinary operation. The material O supporting the conductors on the I-beam J, I prefer to make of 75 hydraulic cement and to fill its pores on the surface with some moisture-proof material, such as oil or soluble glass. In this connection it is particularly desired to use some material which will vitrify rather than carbonize—from the action of lightning, for instance. The working conductors P and Q are insulated and sustained in position by the cement. 80 The trolley may be of either the sliding or rolling variety, somewhat as the form shown 85 in Fig. 3.

It will be noticed more particularly in Fig. 2 that the I-beam which protects the working conductors occupies a higher position than the track-rails. Should a bar of iron or 90 a sleigh-runner, for instance, be across the track it could but make contact with but one of the rails and the I-beam, the idea being to prevent the track-rails from being short-circuited.

It will be understood that the form of working-conductor supports may be used in other distribution systems without departure from the spirit of my invention. For instance, the third rail may be used as the neutral conductor in a three-wire system, or the track-rails may also be employed to carry the main current.

Having thus described my invention, the following is what I claim as new therein and 105 desire to secure by Letters Patent:

1. In a distribution system for electric railways, where the working conductors are located below the cars, an I-beam arranged along the roadway having the working conductors protected by its flanges, said conductors being supported in position by a plastic insulating material and insulated thereby.
2. In a third-rail system, working conductors supported and protected by an I-beam, 115 and insulated therefrom, said beam having its flanges arranged in a horizontal direction, the latter being bent in a curved form substantially as shown so as to stiffen the beam and to leave a dovetailed aperture to retain 120 the insulating material and conductors.
3. In a third-rail system conductors arranged and insulated within the side openings of an I-beam, said beam having its flanges bent together, substantially as shown.
4. An electric-railway system comprising track-sections, sectional working conductors, a direct-current-supply circuit and switching devices connecting same with the working conductors, and a plurality of local circuits 130 each connected to a track-section and including a converting device whereby it is ener-

gized inductively from the supply-circuit, and means in said local circuit for controlling said switching devices.

5. An electric railway comprising track-sections, sectional working conductors, and electromagnetically-controlled switching devices connecting same with the working conductors, electromagnetic semaphore devices, and a plurality of local circuits connected to the track-sections and including the controlling-magnets of said switch and semaphore devices, and subdivided and distributed induction devices connected to the supply-circuit and to the local circuits to energize the latter.

6. An electric-railway system comprising track-sections, sectional working conductors, direct-current-supply conductors and electromagnetically-controlled switches controlling the connection from the supply-conductors to the working conductors, and subdivided and distributed converters energized by the supply-circuit and connected to the track-sections and to the electromagnetic switches to control the latter.

7. An electric-railway system comprising track-sections, a direct-current-supply circuit, sectional conductors and switches controlling their connection with the supply-circuit, local circuits connected to the track-sections and including electromagnets controlling such switches, rotary converters connected to the direct-current-supply circuit, and distributing circuits receiving alternating current from the rotary converters and

including stationary converters connected to energize, by induction, the local track-section circuits.

8. An electric-railway system comprising track-sections, a direct-current-supply circuit, sectional conductors and switches controlling their connection with the supply-circuit, local circuits connected to the track-sections and including electromagnets controlling such switches, electromagnetic semaphores included in the local circuits, rotary converters connected to the direct-current-supply circuit, and distributing-circuits receiving alternating current from the rotary converters and including stationary converters connected to energize, by induction, the local track-section circuits.

9. The combination with the sectional working conductors and the direct-current-supply circuit of electromagnetically-controlled switches controlling the connection from said supply-circuit to the working conductors, track-sections, subdivided and distributed induction devices connected to said track-sections and switching devices, to operate the latter, and means for supplying alternating current to energize said induction devices.

In testimony herewith I have hereunto set my hand and seal, this 7th day of March, A. D. 1901, in the presence of two witnesses.
